UNITED STATES PATENT OFFICE.

GEORGE HENRY WHEARY, OF RACINE, WISCONSIN.

WARDROBE-CABINET.

1,251,947.

Specification of Letters Patent.

Patented Jan. 1, 1918.

Application filed July 24, 1914. Serial No. 852,803.

To all whom it may concern:

Be it known that I, GEORGE HENRY WHEARY, a citizen of the United States, and resident of Racine, in the county of 5 Racine and State of Wisconsin, have invented new and useful Improvements in Wardrobe-Cabinets, of which the following is a description, reference being had to the accompanying drawings, which are a part 10 of this specification.

This invention relates to improvements in wardrobe cabinets.

It is one of the objects of the present invention to provide a wardrobe cabinet having 15 drawers and garment hangers so positioned and arranged as to be conveniently accessible with a minimum effort and without the necessity of disarranging other parts in placing an article of apparel within the 20 cabinet or in removing one therefrom.

A further object of the invention is to provide a wardrobe cabinet having garment hanger tracks mounted therein upon which 25 garment hangers are slidably mounted and independently removable therefrom.

A further object of the invention is to provide a wardrobe cabinet having a plurality of drawers mounted therein which 30 may be independently moved to positions of convenient accessibility.

A further object of the invention is to provide a wardrobe cabinet in which the garment hanger tracks are provided with extensible end portions to permit the garment 35 hangers being slid outwardly thereon and separated whereby the hangers will be more accessible and more easily removed and replaced than heretofore.

A further object of the invention is to 40 provide a means for effectively holding the garments in place and against disarrangement while supported upon hangers within the cabinet.

A further object of the invention is to 45 provide a wardrobe cabinet in which the forward portion of the top is in the form of a hinged door or cover and may be swung upwardly to open position, and when in closed position, overlaps the front door of 50 the cabinet.

A further object of the invention is to provide a wardrobe cabinet having a plu-

rality of hinged doors which are locked in closed position by a plurality of locks controlled by one keyed lock.

55

A further object of the invention is to provide a wardrobe cabinet which is of simple construction, is strong and durable and is well adapted for the purpose described.

With the above and other objects in view, 60 the invention consists of the improved wardrobe cabinet and its parts and combinations as set forth in the claims and all equivalents thereof.

In the accompanying drawings in which 65 the same reference characters indicate the same parts in all of the views:

Figure 1 is a front view of the improved wardrobe cabinet with the doors shown in open position and a portion of the cabinet 70 being broken away to show interior construction;

Fig. 2 is a vertical sectional view thereof taken on line 2—2 of Fig. 1; and

Fig. 3 is a transverse sectional view there- 75 of taken on line 3—3 of Fig. 2.

Referring to the drawings the numeral 5 indicates the cabinet which is of rectangular form and is provided with a front open side 6 covered by a door 7 and a partially open 80 top 8 covered by a top door or cover 9.

The front door 7 is positioned between the projecting front edge portions 10 of the side walls 11 of the cabinet and is hinged to one of the side portions and has a locking engagement with the other side wall. This locking engagement comprises a plurality of spring actuated bolts 12 mounted on the door which engage coacting lock portions 13 mounted on portions of the cabinet. The 90 bolts are controlled by a pull bar 14 slidably mounted on the inner face of the front door and which may be operated when the top door or cover 9 is in open position. This bar extends upwardly and terminates at a 95 point adjacent the upper edge of the door and is provided with a knob or handle 15 for convenience in operating the same. The bar has a slot and pin connection 16 with the lowermost or vertically movable bolt and a 100 bell-crank connection 17 with the uppermost or horizontally slid able bolt 12. This bell-crank also has a pin and slot connection with the bolt so that when the door is closed the

bolts may snap into locked position without moving the bar.

The upper door or cover is provided with front and side flanges 18 which overlap the front door and the side portions of the cabinet and is adapted to be locked to said front door by a keyed lock 19 in the usual manner.

A curved brace arm 20 pivoted to the top door and engaging a coacting member attached to one of the side portions of the cabinet is arranged to hold the said door in open position and at different angles. The top door is provided with a mirror 9' which may be used when the door is swung to open position.

From the description thus far given it will be seen that the front door can not be opened until after the top door has been unlocked 20 and swung upwardly and the locking bar has been pulled upwardly to release the bolts, thus providing a cabinet having a plurality of doors controlled by one keyed lock.

The inner side walls of the cabinet are 25 provided with horizontally extending track bars 21 which are spaced from the walls and supported by vertically extending bars 22 which are secured to said walls. Drawers 23 positioned within the cabinet are provided 30 with hook portions 24 which extend over the track bars and slidably connect the drawers thereto. The drawers are of a width to approximately fill the rear half of the space within the cabinet and thus form the rear 35 half of the space into a drawer section 25 and the forward half of the space into a wardrobe section 26. As the track bar extends from the front to the rear portion of the cabinet, the drawers may be independently pulled outwardly and supported in 40 open position to permit convenient access to the contents thereof when the doors are in open position.

A hanger device 27 mounted on the inner 45 face of the front door comprises a rectangular U-shaped metal strip 28 having extensions 29 hinged to the outer ends of the side or track portions 30 of the device. The hinged connections 31 are provided with 50 stop portions 32 which serve to limit the outward swing of the extensions to longitudinal alignment with their respective track portions. The outer ends of the extensions 29 are provided with a locking means 29' 55 for locking the said ends together when in folded or closed position. When in folded position the garment hangers are held on the fixed tracks by said folded extensions.

Garment hangers 33 having hooked ends 60 34 which extend over the tracks are used in connection with the device and are adapted to support garments draped thereon.

The hanger device is so mounted on the front door that garments draped on the

hangers may be swung within the wardrobe 65 section or outward therefrom to remove or replace the garments on the hangers.

In use the front door may be swung to open position and the extensible tracks swung outwardly so that the garment hangers 70 may be pulled outwardly on the said extensible rails and separated for convenience in removing or replacing a particular hanger or garment.

From the foregoing description it will be 75 seen that all of the space within the cabinet is utilized and that access may be had to the various hangers or drawers.

What I claim as my invention is:

1. A wardrobe cabinet, comprising a casing 80 having an open side and a hinged door therefor and a front garment space and a rear drawer space, a plurality of drawers slidably positioned within the casing and normally positioned in the rear drawer space thereof but independently movable forwardly therefrom and supported in the garment space, parallel track members mounted on the door and extending into the garment space in front of the drawers, 90 extension tracks connected to the outer ends of the track members, and garment hangers slidably mounted on the tracks for supporting garments in the garment space and movable therefrom when the door is swung to 95 open position to permit the drawers to be moved into the garment space.

2. A wardrobe cabinet, comprising a casing 100 having an open side and a hinged door therefor and a front garment space and a rear drawer space, track bars mounted on the opposite side walls of the casing and extending approximately from the front to the rear portion of said casing, drawers positioned within the casing and having hook 105 portions which slidably extend over the track bars and support the drawers therefrom, said drawers normally resting in the drawer space of the casing but being independently movable to a supported position 110 forwardly therefrom into the garment space, a garment hanger device mounted on the door and extending inwardly therefrom into the garment space, and garment hangers slidably mounted on the device for supporting garments in the garment space and movable therefrom when the door is swung to 115 open position to permit the drawers to be moved into the garment space.

3. A wardrobe cabinet, comprising a casing 120 having a front and a top opening and a front garment space and a rear drawer space, doors for said openings, a plurality of drawers positioned in the drawer space of the casing and movable to the garment space thereof and supported in said position, the door covering the top opening permitting access to one of the drawers when said

- drawer has been moved forwardly into the garment space, a hanger device mounted on the door covering the front opening and extending into the garment space in front of the drawers, and garment hangers supported by said device for supporting garments in said garment space and movable therefrom when the door is swung to open position to permit the drawers to be moved into the garment space.
4. A wardrobe cabinet, comprising a casing having a front and a top opening and a front garment space and a rear drawer space, doors for said openings, one of said doors overlapping the other door, a plurality of drawers positioned in the rear drawer space of the casing and movable to the front garment space thereof, the door covering the top opening permitting access to the top drawer when said drawer has been moved forwardly, an extensible hanger device mounted on the door covering the front opening and extending into the garment space in front of the drawers, and garment hangers supported by said device for supporting garments in said garment space and movable therefrom when the door is swung to open position to permit the drawers to be moved into the garment space.
5. A wardrobe cabinet, comprising a casing having a front and a top opening and a front garment space and a rear drawer space, track bars mounted on the opposite inner side portions of the casing and extending approximately from the front to the rear portion of the casing, drawers slidably supported on said track bars and normally positioned in the drawer space of the casing and movable to the garment space of the casing and supported in said position, a door for the front opening of the casing, a door for the top opening of the casing which overlaps the front door, a U-shaped member mounted on and extending inwardly into the garment space from the front door, extensible tracks hinged to the free ends of the inwardly extending ends of the U-shaped member, and garment hangers slidably mounted on the U-shaped member and the tracks for supporting garments in said garment space and movable therefrom when the door is swung to open position to permit the drawers to be moved into the garment space.
6. A wardrobe cabinet, comprising a casing having a front and a top opening and a front garment space and a rear drawer space, track bars mounted on the opposite inner side portions of the casing and extending approximately from the front to the rear portion of the casing, drawers slidably supported on said track bars and normally positioned in the drawer space of the casing and movable to the garment space of the casing and supported in said position, a door for the front opening of the casing, a door for the top opening of the casing which overlaps the front door, a U-shaped member mounted on and extending inwardly into the garment space from the front door, horizontally movable foldable tracks hinged to the outer ends of the U-shaped member, and garment hangers slidably mounted on the U-shaped member and the tracks for supporting garments in said garment space and movable therefrom when the door is swung to open position to permit the drawers to be moved into the garment space.
7. A wardrobe cabinet, comprising a casing having a front and a top opening and a front garment space and a rear drawer space, track bars mounted on the opposite inner side portions of the casing and extending approximately from the front to the rear portion of the casing, drawers slidably supported on said track bars and normally positioned in the drawer space of the casing and movable to the garment space of the casing and supported in said position, a door for the front opening of the casing, a door for the top opening of the casing which overlaps the front door, a U-shaped member mounted on and extending inwardly into the garment space from the front door, extensible tracks hinged to the free ends of the inwardly extending ends of the U-shaped member, and garment hangers slidably mounted on the U-shaped member and the tracks for supporting garments in said garment space and movable therefrom when the door is swung to open position to permit the drawers to be moved into the garment space.
8. A wardrobe cabinet, comprising a casing having a front and a top opening and a front garment space and a rear drawer space, track bars mounted on the opposite inner side portions of the casing and extending approximately from the front to the rear portion of the casing, drawers slidably supported on said track bars and normally positioned in the drawer space of the casing and movable to the garment space of the casing and supported in said position, a door for the front opening of the casing, a door for the top opening of the casing which overlaps the front door, a U-shaped member mounted on and extending inwardly into the garment space from the front door, horizontally movable foldable tracks hinged to the outer ends of the U-shaped member, and garment hangers slidably mounted on the U-shaped member and the tracks for supporting garments in said garment space and movable therefrom when the door is swung to open position to permit the drawers to be moved into the garment space.
9. A wardrobe cabinet, comprising a casing having a front and a top opening, a door for the front opening, a door for the top opening and having a portion which overlaps the front door, a plurality of draw-

ers within the casing, a hanger device mounted on the front door and extending into the casing, a bolt means for locking the front door to the casing, a member controlling the bolt means and extending to an operable position adjacent the top door, and a locking means for the top door.

10. A wardrobe cabinet, comprising a casing having a front and a top opening, a door 10 for the front opening, a door for the top opening and having a portion which overlaps the front door, a plurality of drawers within the casing, a hanger device mounted on the front door and extending into the

casing, a plurality of bolts locking the front 15 door to the casing, a bar connected to the bolts and extending to a position adjacent to the top door, said bar moving the bolts to open position when moved and controlled by the position of the top door, and a keyed 20 locking means for the top door.

In testimony whereof I affix my signature in presence of two witnesses.

GEORGE HENRY WHEARY.
